UNITED STATES PATENT OFFICE.

PETER PETRY, OF NEWARK, NEW JERSEY.

DESIGN FOR HARNESS-TRIMMINGS.

SPECIFICATION forming part of Design No. 12,408, dated August 9, 1881.

Application filed June 28, 1881. Term of patent 3½ years.

To all whom it may concern:

Be it known that I, PETER PETRY, of Newark, in the county of Essex and State of New Jersey, have invented and produced a new and original Improvement in Designs for Harness-Trimmings, of which the following is a specification.

Figure 1 is a side elevation of a terret. Fig. 2 is an edge view of the same. Fig. 3 is a side elevation of a post-hook. These are representative articles, and all the parts of the harness-trimmings—as buckles, hooks, &c.—will be made up after this pattern.

The leading features of my design are, first, the bow or loop portion A in the form shown, but having transversely a rounded exterior, as seen at B in Fig. 2; second, from the point

B the sides tapering down to the lower end, C; third, the cross-section D uniting with the sides and the base in the form shown, and having the edges E flush with the edges of the loop portion A.

I claim—

The terret, hook, or other harness-trimming, having the bow shape A with the rounded external surface, B, the tapering sides down to C, and the cross-section D, in the form shown, and having the edges E flush with the edges of the loop portion, substantially as set forth.

PETER PETRY.
